US00D889913S

(12) **United States Design Patent** (10) Patent No.: **US D889,913 S**
Seiders et al. (45) Date of Patent: ** Jul. 14, 2020

(54) **BOTTLE**(71) Applicant: **YETI Coolers, LLC**, Austin, TX (US)(72) Inventors: **Roy Joseph Seiders**, Austin, TX (US);
Steve Charles Nichols, Austin, TX (US); **Matthew Joseph Petrillo**, Austin, TX (US)(73) Assignee: **YETI Coolers, LLC**, Austin, TX (US)(***) Term: **15 Years**(21) Appl. No.: **29/710,243**(22) Filed: **Oct. 22, 2019****Related U.S. Application Data**

(63) Continuation of application No. 29/653,729, filed on Jun. 18, 2018, now Pat. No. Des. 872,542, which is a continuation of application No. 29/618,680, filed on Sep. 22, 2017, now Pat. No. Des. 820,650, which is a continuation of application No. 29/605,464, filed on May 26, 2017, now Pat. No. Des. 799,908, which is a continuation of application No. 29/544,197, filed on Oct. 30, 2015, now Pat. No. Des. 804,255.

CLAIM

The ornamental design for a bottle, as shown and described.

DESCRIPTION

FIG. 1 is a top, front, right perspective view of a bottle showing our new design;

FIG. 2 is a front view thereof, wherein the rear view is a mirror image of FIG. 2;

FIG. 3 is a right side view thereof, wherein the left side view is a mirror image of FIG. 3; and,

FIG. 4 is a top view thereof.

The uneven broken lines immediately adjacent to the shaded area define the bounds of the claimed design and form no part thereof. The even length broken lines depicting the remainder of the bottle show features that form no part of the claimed design.
